HYDRAULIC ELEVATOR CONTROL
James Frank MacNair, Bronx, and Peter J. Scully, Brentwood, N.Y., assignors to Hydraulic Elevator & Machine Company, Inc., Brooklyn, N.Y., a corporation of New York

Filed Sept. 6, 1961, Ser. No. 136,276
11 Claims. (Cl. 187—29)

This invention relates in general to hydraulic elevator controls and in particular to an automatic speed control system which provides overspeed protection, speed equalization, and smooth acceleration and deceleration in hydraulic elevator installations. The invention can be utilized in any hydraulic elevator system, but it is particularly useful in automatic elevator control systems such as described, for example, in U.S. Patent Number 2,913,070, which was issued on November 17, 1959, to Magnus N. Nyberg for an "Automatic Elevator Control."

Hydraulic elevator systems were superseded forty years ago by electric elevator systems, which are much smoother in operation and much easier to control than their hydraulic counterparts. Before this happened, however, many large buildings were erected all over the world with hydraulic elevator systems, and a large number of these hydraulic elevator systems are still in operation today. In New York City alone there are approximately 300 buildings which use hydraulic elevator systems. As it happens, the structural requirements for hydraulic elevators differ so radically from those for electric elevators that these installations cannot be changed without major structural alterations in the entire building. In most cases the necessary structural alterations are out of the question, for one reason or another, so that these hydraulic elevator systems will stay in service until their buildings are torn down and rebuilt. Therefore any improvements or modernization of the elevator service in these buildings must be made by improving the hydraulic elevator systems therein rather than replacing them with electric systems.

One such improvement is described in the above noted U.S. Patent Number 2,913,070, which discloses an automatic electric control circuit that replaces the cumbersome, slow acting, mechanical control systems formerly used in hydraulic elevator systems. This automatic control system obviates the requirement for skilled operators, and provides a completely automatic control system, which can be operated by the passengers if desired. But although this automatic control system was a vast improvement over manual control systems, it was by no means perfect. It delivered the passengers to their selected floors, but it gave them a rough, jarring ride in transit, particularly in the deceleration period when the elevator was approaching the selected floor. Furthermore, the system did not provide any means for equalizing elevator speed under different load conditions, whereby a heavily loaded car would move up like a snail and down like a rock while a lightly loaded car would do the opposite. In addition, the system did not provide for overspeed protection and the elevator cars were therefore liable to build up so much speed as to frighten the passengers, to give them a severe jolt when the car stopped, and to overshoot the selected stop.

2

This invention is addressed to the problems which were unsolved in these prior art improvements—the problems of (1) equalizing speed under varying load conditions, (2) providing smooth, effective overspeed protection, and (3) providing smooth acceleration and deceleration. Many different methods have been used in the past in an attempt to solve these problems, but none of these prior art methods have proved workable in practice. For example, some prior art systems have tried to equalize speed by counting the number of passengers entering a car and then selecting a hydraulic drive setting based on the number of persons in the car multiplied by their hypothetical average weight. The passengers were counted by a photocell counter circuit in the car, and the hydraulic drive setting was selected in a variable hydraulic drive circuit which could be adjusted in predetermined increments in response to a signal from the photocell counter. This system, however, was an approximation at best, and in practice it was subject to grave defects. In the first place, it was relatively complex in structure and its complexity encouraged circuit failure or mis-operation. In the second place, errors were cumulative in the circuit. If the counter added a count, as counters sometimes do, these erroneous counts would accumulate from one trip to the next until the counter would indicate a full condition on an empty car. This, of course, produced a worse ride than an unequalized drive system. And finally, the counter method of equalization was not useful in solving the other two problems—smoothing deceleration and providing overspeed protection.

The deceleration problem has, in the prior art, been approached by a speed increment system similar to those used in the prior art speed equalizing systems. The speed of the car was decreased by timed increments instead of by a sudden switch from top speed to approach speed. This method, however, was also relatively complex in structure and relatively unreliable in operation. In practice it multiplied the number of jolts instead of producing a smooth transition from high speed to approach speed, and it complicated the problem of reaching the correct approach speed to achieve exact leveling without overshoot. Since the reduction of speed was timed in accordance with a hypothetical average car speed, the deceleration was too fast on slow moving cars and too slow on fast moving cars. Furthermore, this speed increment system made no contribution to overspeed protection.

The prior art approach to overspeed protection was based on a governor which was coupled between the elevator drive shaft and the hydraulic valves which controlled the movement of the drive shaft. As the speed of the drive shaft increased the governor would close the hydraulic valves via a mechanical linkage and as the speed of the drive shaft decreased the governor would open the hydraulic valves. This method, however, was unsatisfactory in practice because it takes much more force to close a hydraulic valve than it does to open the valve. Therefore when the governor cut in the car would slow down with a jolt and then accelerate slowly until the governor cut in again, whereupon the car would slow down with another jolt. This produced a very unpleasant sensation, particularly on long rides in a heavily loaded car.

Other methods of solving the problems of speed equalization, smooth deceleration, and overspeed protection

have been proposed in the past, but in general they have all suffered from the above noted disadvantages—i.e. they have applied to only one of the three problems instead of to all three, they have been unduly complex in nature and unreliable in operation, they have been based on hypothetical quantities, and they have not provided an adequate solution to their particular one of the three problems let alone to all three at once. In addition to these disadvantages, the prior art speed control systems have suffered from a more serious handicap in that their action was based on factors which vary from elevator to elevator, whereby each speed control system had to be tailor made for its particular application.

Accordingly, one object of this invention is to provide a hydraulic elevator control system which provides overspeed protection, speed equalization, and smooth deceleration in hydraulic elevator installations.

Another object of this invention is to provide an automatic speed control system which simultaneously provides overspeed protection, speed equalization, and smooth deceleration in hydraulic elevator installations.

A further object of this invention is to provide an automatic speed control system of the above noted type which is simpler in structure and more reliable in operation than those heretofore known in the art.

An additional object of this invention is to provide an automatic speed control system of the above noted type which is smoother in operation and more effective than those heretofore known in the art.

Another object of this invention is to provide an automatic speed control system of the above noted type which can be applied to widely varying elevator installations without any significant changes in the automatic speed control circuit or in the elevator system.

A further object of this invention is to provide an automatic speed control system of the above noted type which is less expensive to manufacture, easier to install, and easier to maintain than those heretofore known in the art.

Other objects and advantages of this invention will be apparent to those skilled in the art from the following description of one specific embodiment, as illustrated in the attached drawings, in which:

FIG. 1 is a block diagram of one illustrative hydraulic elevator and automatic elevator control system incorporating the automatic speed control of this invention;

FIG. 2 is an elevation section of one illustrative selector switch means and hydraulic control means for the elevator system of FIG. 1;

FIG. 3 is a schematic diagram showing one illustrative arrangement of brushes and brush wipers for the selector switch means shown in FIG. 2;

FIG. 4a is a schematic diagram of one portion of an illustrative circuit arrangement for the valve control circuit of FIG. 1;

FIG. 4b is a schematic diagram of the remaining portions of the circuit shown in FIG. 4a; and

FIG. 5 is a schematic diagram of the speed correction circuit.

Although the speed control system of this invention can be used with any hydraulic elevator, it is particularly useful in connection with hydraulic elevators containing automatic control systems, such as disclosed in the above noted U.S. Patent Number 2,913,070, and this invention will therefore be described in connection with an automatic elevator control system of that type. In FIGS. 1 and 2 the structural elements numbered 10 through 68 are identical with the structural elements disclosed in FIGS. 1 and 2 of the above noted U.S. Patent Number 2,913,070, except for valves 24c, 24d, 26c, and 26d, and the structural elements numbered 70 through 92 and 24c, 24d, 26c, and 26d correspond to the novel structure of this invention.

The prior art portions of FIG. 1 show a hydraulic elevator system in which an elevator car 10 is positioned

up and down an elevator shaft by means of a hydraulic ram 12. As the elevator car 10 moves from floor to floor a synchro generator 14, which is coupled to a counterweight pulley shaft 16, feeds back signals to synchro motor 18 indicating the actual instantaneous elevation of the elevator car. When an operator wishes to move the elevator to a different floor, he depresses the push button associated with the desired floor on a floor selector panel 20, which generates a signal indicating the selected floor. This signal is coupled to electrical control means 22. At the same time, synchro motor 18 transmits a signal to electrical control means 22 indicating the present level of the elevator car 10. These two signals are compared in the electrical control means 22 and if the selected floor is below the present position of the elevator car, the down valve means 24 will be energized, causing the hydraulic control means 28 to bleed fluid from the hydraulic ram 12, thus moving the car downward. When the elevator car reaches the selected floor, the electrical control means 22 de-energizes the down valve means 24 and the hydraulic ram stops. If, on the other hand, the selected floor is above the present level of the elevator car, the electrical control means 22 will energize the up valve means 26. Hydraulic control means 28 will then feed fluid into hydraulic ram 12, and the elevator car will start on an upward motion. This upward motion continues until the selected floor and the indicated floor are the same. At this time the up valve means 26 is de-energized and the hydraulic ram stops.

In accordance with the novel features of this invention the speed of the elevator car 10 is controlled by means of a valve control circuit 70 which is coupled between electrical control means 22 and valve means 24 and 26. Valve control circuit 70 receives a signal indicating the elevator car's actual speed of movement from a tachometer 72 which is also coupled to counterweight pulley shaft 16. Valve control circuit 70 also receives signals indicating the actual state of hydraulic control means 28 from selector switch means 74 which is mechanically coupled to the movable part of hydraulic control means 28. Valve control circuit 70 also receives signals from electric control means 22, which selects the direction of movement and the starting and stopping times as in the prior art. Valve control circuit 70 is adapted to correlate these various input signals in such manner as to provide equalization of speed under varying loads, smooth acceleration and deceleration, and overspeed protection as will be described in greater detail below.

FIG. 2 shows one illustrative hydraulic control means, up and down valve means, and selector switch means which can be used in the elevator system illustrated in FIG. 1. The structural elements numbered 12 through 68 are identical with the structural elements disclosed and described in the above noted U.S. Patent Number 2,913,070, except for valves 24c, 24d, 26c, and 26d and the structural elements numbered 74 through 92 and 24c, 24d, 26c and 26d are the novel structure of this invention. The numbers on the prior art elements in FIG. 2 are the same as those used in the above noted patent and the function of these prior art elements is identical in this invention whereby the description given on columns 2 and 3 of the above noted patent will be valid except for the modifications noted below. In the prior art portions of the structure, hydraulic fluid is driven into hydraulic ram 12 when valve stem 40 is moved downward from the neutral position shown in FIG. 2, and hydraulic fluid is bled from hydraulic ram 12 when valve stem 40 is moved upward from its neutral position. The position of valve stem 40 is controlled by solenoid operated valves 24a, 24b, 26a, and 26b, which operate in conjunction with a pilot valve 32 to control the fluid pressure in fluid chamber 36. In the upward position of valve stem 40, pilot valve 32 is positioned so as to open a fluid conduction path between valve ports 52 and

56 thereof, which connects conduit 57 to conduit 68. In the downward position of valve stem 40, pilot valve 32 is positioned so as to open a fluid conduction path between valve ports 52 and 54 thereof. This connects conduit 57 to conduit 58. In the neutral position of valve stem 40, pilot valve 32 is also positioned in a neutral position, i.e. a position in which valve port 52 is closed so that conduit 57 is not coupled to either of the other two conduits. When valves 24a, 24b, 26a, and 26b are de-energized, valve stem 40 will be driven to its neutral position by the action of pilot valve 32, which will couple the fluid source to fluid chamber 36 if valve stem 40 is above its neutral position and which will couple the fluid sink to fluid chamber 36 if valve stem 40 is below its neutral position.

To raise elevator car 10, the valve stem 40 of the hydraulic valve control means is moved to its downward position by energizing solenoid valve 26a and 26b. Valve 26a introduces fluid from the fluid source into fluid chamber 36 and thus drives valve stem 40 downward. (The fluid sink is isolated from conduit 58 by valve 26b, which is closed in the energized state thereof.) When solenoid valve 26a and 26b are de-energized, valve 26b couples the fluid sink to fluid chamber 36 via conduit 58, valve ports 54 and 52, and conduit 57, thus moving valve stem 40 upward to its neutral position. To lower elevator car 10, solenoid valves 24a and 24b are energized, which couples the fluid sink to fluid chamber 36 through valve 24a, thus driving valve stem 40 upward. When solenoids 24a and 24b are de-energized, the fluid source is coupled to fluid chamber 36 via conduit 68, valve ports 56 and 52, and conduit 57.

It can be seen, then, that the "up" and "down" valve means operate in pairs, the normally closed member of the pair acting to couple either the fluid source or the fluid sink to fluid chamber 36 to initiate the upward or downward movement of valve stem 40, and the normally open member of the pair acting to reverse the coupling and re-center valve stem 40 when the valves are de-energized. In this prior art arrangement, the hydraulic control means is driven either to its full open or full closed position by the "up" and "down" valve means, and is held in a neutral position in the absence of a signal to either the "up" or "down" valve means. In accordance with this invention, however, novel structure is added to partially open and partially close the hydraulic valve means to achieve slow acceleration or deceleration and also to move valve stem 40 upwardly or downwardly to compensate for overspeed or to decelerate the elevator in the approached zone. This is done quite simply by adding small solenoid valves 24c, 24d, 26c, and 26d in parallel with the prior art control valve and by coupling selector switch 74 to valve stem 40 to determine the actual position thereof. In this particular embodiment of the invention, the selector switch comprises a stationary plate 76 containing brushes and brush wipers and a movable plate 78 containing brushes and brush wipers which engage the brushes and brush wipers on plate 76. The brushes and brush wipers are indicated schematically in FIG. 2 by the tooth-like projections on the surface of plates 76 and 78. Movable plate 78 is coupled via pulleys 80 and 82 to the top of valve stem 40 and therefore moves up and down in synchronism with the movement of valve stem 40. The brushes and brush wipers on plates 76 and 78 are adapted to provide signals which indicate the approximate speed of the elevator car and these signals are used to control valve control circuit 70 to approximate the desired speed conditions.

In accordance with this invention valves 26a and 26b are only energized during the high acceleration portion of the upward or downward travel. As soon as valve stem 40 reaches a position indicating that top speed is being approached, valve 26a (or 24a) is cut out of the circuit and is replaced by smaller valve 26c (or 24c) 70

for the duration of the upward or downward travel. Since valves 24c and 26c are smaller than valves 24a and 26a, the acceleration will continue at a much slower rate when top speed is approached. If the top speed is exceeded during the upward or downward travel, valves 24d or 26d are opened, by valve control circuit 70, until the speed of elevator car 10 drops back to its rated top speed. The circuit that opens valves 24d and 26d is responsive to tachometer 72, which measures the actual speed of elevator car 10. When elevator car 10 is near its selected floor, the valves are de-energized and normally open valves 24b or 26b return valve stem 40 toward its neutral position until the desired approach speed is reached. If the elevator car does not come down to its proper approach speed, valves 24d or 26d will be opened again to decelerate down to the proper speed so that the elevator car will not overshoot the selected floor. If the elevator car is traveling at or slightly below its rated top speed it will decelerate smoothly down to the proper approach speed without any opening of valves 24d or 26d. And if the elevator car reaches the proper approach speed before it comes into the leveling zone, which extends one foot above and below the desired level, the elevator car will come to rest at the desired level without any overshoot.

It should be noted here that the tachometer means could be used by itself to perform the above noted functions, but that the combination of a tachometer with a selector switch is preferable because it provides a significant simplification in the valve control circuit. The position of the brushes on the selector switch does not indicate the exact speed of the elevator car, since the exact speed varies as a function of load, but the position of the brushes will indicate the approximate speed within a relatively large but predetermined tolerance. Therefore the valve stem of the hydraulic control means can be positioned to an approximately correct position by a simple switching circuit which is responsive to the selector switch, and any errors due to a change in the load condition can be corrected in an equally simple correction circuit which is responsive to the tachometer. This combination provides the desirable objectives of smooth acceleration and deceleration, speed equalization, and overspeed protection without the drawbacks of complex and unreliable control circuits. It should be understood, however, that the selector switch and its associated circuits could be used independently of the tachometer and its associated circuits if desired, and that the tachometer and its associated circuits could also be used independently of the selector switch and its associated circuits. In its basic form, this invention comprises (1) a novel approximate speed control device comprising the selector switch and its associated structural elements, (2) a novel speed correction device comprising the tachometer and its associated structural elements, and (3) a novel automatic speed control system comprising the selector switch, the tachometer, and their associated structural elements.

FIG. 3 shows one illustrative layout for the brushes and brush wipers of selector switch 74 in this particular embodiment of the invention. There are two symmetrical sets of brushes on movable plate 78; one set corresponding to the up direction of elevator travel, and the other set corresponding to the down direction of elevator travel. The "up" brushes are indicated by the letter U in their designation while the "down" brushes are indicated by the letter D in their designation. Stationary plate 76 contains a single set of brushes and brush wipers which are adapted to engage the "up" brushes of movable plate 78 when the elevator is moving upward and to engage the "down" brushes of movable plate 78 when the elevator is moving downward. The brushes and their corresponding wipers are adapted to make and break contact at predetermined approximate speeds. The approximate speed is, of course, directly related to the position of the hydraulic valve means, although the exact relationship might differ in

some elevator installations. This relationship, however, can be easily determined by well known prior art techniques so that the brushes can be set to make or break at any desired approximate speed.

FIGS. 4a and 4b show one illustrative circuit which can be used to embody valve control circuit 70 with the particular selector switch layout shown in FIG. 3. In the circuit of FIG. 4a, the relay contacts marked UM, DM, SP, LV, and APP are actuated by relays in electrical control means 22 or in the elevator shaft. All of the other contacts are actuated by relays shown in FIG. 4b. Electrical control circuit 22 can be any suitable prior art elevator control circuit which provides the following signal inputs to the valve control circuit of this invention: (1) an "up" signal indicating that the elevator car is to begin moving upward (this signal actuates all of the UM contacts shown in FIG. 4a); (2) a "down" signal indicating that the elevator car is to begin moving downward (this signal actuates all of the DM contacts shown in FIG. 4a); a "high speed" signal indicating the elevator car is to make a long run (this signal actuates the SP contacts shown in FIG. 4a); a "low speed" signal indicating that the elevator car is to make a short run (this signal momentarily actuates the SP contacts shown in FIG. 4); a "high speed approach zone" signal indicating that the elevator car has reached the approach zone for its selected floor under high speed conditions (this signal de-actuates the SP contacts shown in FIG. 4a); a "low speed approach zone" signal indicating that the elevator car has reached the approach zone for its selected floor under low speed conditions (this signal actuates the APP contacts shown in FIG. 4a); and a "leveling zone" signal indicating that the elevator car has reached the leveling zone for its selected floor (this signal actuates the LV contacts shown in FIG. 4a). In addition to these input signals from electrical control means 22, the valve control circuit of FIG. 4b also receives an input signal from tachometer 72 and several inputs from selector switch 74, whose individual brushes and brush wipers are identified by the same designations used in FIG. 3. The relay contacts and brushes are separated from their solenoids in FIG. 4a and FIG. 4b for clarity of illustration, but it will be understood by those skilled in the art that contacts with the same designation are actuated simultaneously by the solenoid having the corresponding designation.

In describing the overall operation of the valve control circuit, it will be useful to first describe the speed correction portions of the circuit and then to present some exemplary sequences of operation for the circuit as a whole. Referring to FIG. 5, tachometer 72 is coupled to relay meters 84, 86, and 88, which can comprise any suitable prior art relay meter such as the Simpson model 29X voltmeter or the like. Each relay meter has a coil, which is indicated in FIG. 5 by the resistor within the box denoting the relay meter, and a relay contact circuit comprising the needle of the meter and two stationary contacts which can be adjusted to contact the needle of the meter at any predetermined point in its positive or negative direction of travel. The needle of the meter rests in the center position in the absence of a voltage input and travels either to the right or to the left when a voltage is applied thereto, depending upon the polarity of the voltage. The deflection of the needle, of course, is proportional to the magnitude of the applied voltage. The coils of all three relay meters are coupled in parallel to tachometer 72, which can be any suitable tachometer generator that produces a D.C. voltage output proportional to its speed of rotation. The scales of the relay meters are preferably calibrated in terms of speed rather than voltage to facilitate adjustment of the stationary contacts to intercept the needle at any desired speed.

In this particular embodiment of the invention, relay meter 88 is adapted to close its contacts when the elevator reaches its normal running speed; relay meter 86 is adapted to close its contacts when the elevator reaches its

normal approach speed; and relay meter 84 is adapted to close its contacts when the elevator exceeds its maximum speed. The specific values of these speeds will, of course, depend upon the particular elevator installation for which the circuit is designed, so that the exact speed values cannot be specified in general. For purposes of explanation, however, it will be assumed that relay meter 88 is set to close at a speed of 400 feet per minute, and that relay meter 86 is set to close at 110 feet per minute, and that relay meter 84 is set to close at 440 feet per minute. The operation of the relay meters and their associated circuits can be best described by running through a typical operating cycle thereof. Assume that an "up" signal or a "down" signal is received from electrical control means 22 to initiate an upward or a downward movement of the elevator. The "up" or "down" signal actuates all of the UM or DM contacts in the valve control circuit, whereby voltage is applied to rectifier 90 by way of contacts UM₄ or DM₄, thereby developing a positive D.C. voltage on the needle of each relay meter and a negative D.C. voltage on the solenoid circuits coupled to the stationary contacts of the relay meters. Other UM or DM contacts actuate the "up" or "down" valve means, and the elevator starts to move in the specified direction. When the elevator begins its motion, tachometer 72 starts to develop a voltage output proportional to the instantaneous speed of the elevator. As the speed of the elevator rises, the output voltage of tachometer 72 rises until the elevator reaches its normal running speed of 400 feet per minute, at which time the contacts of relay meter 88 close. (Relay meter 86, which closes at 110 feet per minute, is initially removed from the circuit by normally open contacts VSU₁ and VSD₁, which do not close until the elevator is decelerating to its approach speed.) When the contacts of relay meter 88 close, solenoid TAC3 is energized via diode D1, normally closed contacts TACD₁, and normally closed contacts TAC3₁. As soon as solenoid TAC3 is actuated it shuts itself off by opening normally closed contacts TAC3₁. A resistor R1 and capacitor C1 are coupled in parallel with solenoid TAC3 to hold the solenoid energized momentarily after its circuit is broken by the opening of contacts TAC3₁. Capacitor C1 stores electrical energy while contacts TAC3₁ are closed and discharges its energy as soon as they open. The time constant of this RC circuit is chosen to hold solenoid TAC3 energized long enough to allow solenoid TAC4 to be energized by normally open contacts TAC3₂. After energizing solenoid TAC4, solenoid TAC3 is de-energized by the discharge of capacitor C1 while solenoid TAC4 latches itself closed by means of contacts TAC4₂ and also opens the circuit to the coil of relay meter 88 and to the solenoid of TAC3 through normally closed contacts TAC4₃ and TAC4₁. The diode D1 in series with solenoid TAC3 protects relay meter 88 and rectifier 90 from the inductive kickback voltage which arises when the current through solenoid TAC3 is interrupted. Resistor R1 and capacitor C1 further reduce the inductive kickback by smoothing the transition between the energized and de-energized states of the solenoid. In summary, the closure of relay meter 88 acts to energize solenoid TAC4, which indicates that the elevator has reached its normal running speed, and to remove relay meter 88 from the circuit for the duration of the elevator run to protect its contacts from being overloaded. The actuation of solenoid TAC4 switches other circuits that terminate motion in the hydraulic control means to theoretically hold the elevator at its normal running speed.

In certain circumstances, however, the elevator may continue to accelerate after having reached its normal running speed until it exceeds its maximum speed of 440 feet per minute. This occurs, for example, in a heavily loaded car which is moving downwardly. When the maximum speed is reached, the contacts of relay meter 84 will close, which will momentarily energize solenoid TAC through diode D2 and normally closed contacts TAC₁. Before solenoid TAC has time to energize, however, the

voltage applied through diode D2 will be coupled directly to capacitor C2 through normally closed contacts TAC₂. This will charge capacitor C2 up to the full value of the D.C. output voltage of rectifier 90. When the contacts of solenoid TAC close, however, the solenoid circuit is immediately broken by the opening of contacts TAC₁ and capacitor C2 is coupled to resistors R2 and R3 by the opening of contacts TAC₂. Capacitor C2 then discharges through resistors R2 and R3 to hold solenoid TAC in the energized conditions for some predetermined length of time which is controlled by the setting of R3. When capacitor C2 has discharged, solenoid TAC will be de-energized, but as soon as it returns to the de-energized state it will be immediately re-energized if the contacts of relay meter 84 are still closed. (Diode D2 protects relay meter 84 and rectifier 90 from inductive kickback.) Thus solenoid TAC will produce periodic pulses as long as the contacts of relay meter 84 remain closed. The time duration of these pulses is adjustable within a reasonable range by the setting of variable resistor R3. This pulsation is transferred to solenoid TAC₂ by means of contacts TAC₃ so that solenoid TAC₂ will also produce periodic pulses of a predetermined time duration as long as the contacts of relay meter 84 remain closed. (Resistor R4 protects the contacts of relay meter 84 when they open.) The pulsations of TAC₂ are coupled to the elevator speed reduction valve described previously, and each pulse serves to reduce the speed of the elevator by a speed increment which is proportional to the duration of the pulse. Thus the pulses will reduce the elevator's speed by small increments until it falls below the rated top speed of 440 feet per minute at which time the contacts of relay meter 84 will open again and the pulsations will cease.

The frequency of the above described pulsations is determined jointly by the response time of relays TAC and TAC₂ and the pulse duration selected by the setting of adjustable resistor R3. It is not possible to specify the exact frequency or pulse duration of the circuit, however, because the best frequency and pulse duration will be determined by the particular hydraulic valve means used in connection with the circuit and the particular elevator system with which the elevator is used. It should be noted, however, that a pulsating overspeed protection circuit is not essential to the basic form of this invention. The pulsating circuit of this particular embodiment is used to protect the meter relay contacts from being welded by inductive kickback current when relay TAC is de-energized. With the pulsating meter circuit, the relay meter contacts only act to make the TAC relay circuit, which then breaks itself. This protects the relay meter contacts from the inductive kickback current. If a buffer amplifier is coupled between the meter relay contacts and the TAC relay, however, relay TAC could be energized continuously as long as the meter relay contacts remain closed. The overspeed circuit would operate in the manner described above except that the elevator would be decelerated continuously until it drops below its maximum speed instead of being decelerated in pulses. The above described overspeed circuits can be mechanized by many other suitable circuit arrangements which will be apparent to those skilled in the art. For example, the relay meters could be replaced by electronic threshold circuits of one type or another, and the relays could be replaced by flip-flops if desired.

Due to the action of the above described overspeed circuit, the elevator will be traveling somewhere between its normal running speed of 400 feet per minute and its maximum speed of 440 feet per minute when it enters the approach zone for its selected floor. In this particular example the approach zone extends for approximately 15 feet above and below the selected floor level. When the elevator enters the approach zone for its selected floor, a set of approach contacts close in the elevator shaft and a "decelerate" signal is generated by electrical control means 22 to initiate deceleration to the approach

speed of 110 feet per minute. In the valve control circuit this "decelerate" signal returns all of the SP contacts to their normal condition, which begins a smooth deceleration process in the hydraulic control means. At the time 5 the elevator should have theoretically reached its approach speed, the VSU or VSD relay is energized, which closes the circuit to the coil of relay meter 86 through normally closed contacts SP₁ and normally open contacts VSU₁ or VSD₁. If the elevator is going faster than its 10 desired approach speed, the contacts of relay meter 86 will close and the elevator will be pulsed down to its approach speed by the same pulser circuit which was used to limit the elevator's maximum speed. The elevator will then come into its leveling zone at the correct 15 approach speed so that it will come to rest at its selected floor level without overshoot. The leveling zone in this particular example extends approximately one foot above and below the selected floor level. When the elevator comes into the leveling zone the UM or DM and VSU 20 or VSD contacts return to their normal condition and solenoid TAC₄ is de-energized. This returns the valve control circuit to its original condition and the hydraulic control means then returns to its neutral position, thus 25 smoothly decelerating the elevator from its approach speed to a stop at the selected floor.

The other portions of the valve control circuit can also be best explained by running through some illustrative elevator operating cycle. Assume, for example, that the elevator receives a signal from electrical control 30 circuit 22 indicating that the elevator car is to move upward on a long run (two or more floors). This signal actuates all of the UM and SP contacts shown in the circuitry of FIG. 4a. The first effect of these closures is to apply power to all of the solenoid circuits through 35 normally open contacts UM₅ and to energize solenoids UF, UFA, and USA through their respective UM and SP contacts. These solenoids in turn energize control valves 26a, 26b, and 26c, which start the elevator moving upward at a relatively high rate of acceleration. In this 40 particular embodiment of the invention, the CU contacts of selector switch 74 break when the elevator reaches a speed of approximately 300 feet per minute, thereby de-energizing solenoid UFA and dropping out the large valve 26a (FIG. 2), thus reducing the elevator's rate of acceleration. 45 The elevator then continues to accelerate toward the normal running speed but at a slower rate which is determined by the size of small valve 26c. When the elevator's speed reaches approximately 360 feet per minute, contacts DU of selector switch 74 make up, thereby 50 energizing solenoid UP which latches itself closed via normally open contacts UP₁. Solenoid UP provides an extra measure of overspeed protection for the circuit. If, for example, a short were to exist around the CU brushes of selector switch 74, the UFA solenoid would not drop out when it was supposed to and the elevator would continue to increase its speed at a high rate of acceleration. 55 This possibility is precluded by the opening of normally closed contacts UP₃ which will de-energize the UFA solenoid even if the CU brushes are shorted. Solenoid UP also energizes solenoid HS, which latches itself closed through normally open contacts HS₁. Solenoid HS acts to open up the circuit to the single floor (slow speed) solenoids X, XU, and XD so that they will be removed from the circuit in a high speed run. The X, 60 XU, and XD solenoids are only used on single floor runs, which will be described later.

After the DU contacts have made up, the elevator continues to accelerate at a low rate of acceleration until it reaches its normal running speed of 400 feet per minute 65 at which time solenoid TAC₄ will be energized by relay meter 88 as described previously. When solenoid TAC₄ is energized, solenoid UAL will be energized via normally open contacts TAC₄ and UM₃, and this will de-energize solenoid USA by opening normally closed contacts UAL₁. As a safety measure, normally closed con-

tacts UAL₂ are added in series with solenoid UFA to de-energize this solenoid in case the CU brushes should be short circuited and the DU brushes or the UP solenoid open circuited. Therefore when solenoid UAL is energized, control valves 26a and 26c will both be de-energized and the hydraulic control means will remain fixed in position so as to terminate all acceleration due to movement of the hydraulic control means. Under ideal conditions this would hold the elevator at its normal running speed of 400 feet per minute.

But suppose, for one reason or another, that the elevator continues to accelerate after it has reached its normal running speed and that its speed exceeds the maximum speed of 440 feet per minute. This can happen when an empty car is moved upwardly, or when a fully loaded car is moved downwardly, or when leakage develops in normally closed valves 24a or 26a. In this case the pulsating overspeed circuit will be actuated and solenoid TAC2 will pulsate as long as the overspeed condition persists. The pulsation of solenoid TAC2 will actuate solenoid USD via normally opening contacts TAC2₁, and the pulsations of solenoid USD will pulsate the hydraulic decelerating valve 26d by means of normally open contacts USD₁ and USD₂. The elevator will then be decelerated by predetermined increments until it has fallen below the maximum speed, at which time the pulsations will terminate. The overspeed circuit will cut in as often as necessary to hold the elevator below its maximum speed during the run.

When the elevator reaches the approach zone for its selected floor, all of the SP contacts will return to their normal condition, in response to a signal from electrical control means 22, and solenoid UF will be de-energized, thereby de-energizing control valve 26b. When control valve 26b is de-energized the elevator starts to decelerate down toward its approach speed, and the deceleration process is stopped by re-energizing solenoid UF when the approximate approach speed is reached. Solenoid UF is re-energized through normally open contacts VSU₂, which are actuated by the closure of the BU contacts on selector switch means 74. The BU contacts are set to make at approximately 280 feet per minute, but since the hydraulic valve means is in motion when the BU contacts make, and since a certain amount of time is required to close the contacts of solenoid VSU, the elevator speed should under normal conditions be decelerated down to about 110 feet per minute when the UF solenoid is re-energized. The UF solenoid re-energizes hydraulic control valve 26b to terminate deceleration of the elevator. If the elevator speed is above 110 feet per minute when the deceleration period is terminated, however, the elevator will be pulsed down to the correct approach speed by means of solenoid USD and solenoid TAC2, which will be pulsed by relay meter 86 until the elevator drops below the correct approach speed.

When the elevator comes into its leveling zone, solenoid VSU will be de-energized by the opening of normally closed contacts LV₁, thereby de-energizing solenoid UF for a second time and de-energizing hydraulic control valve 26b for a second time. At the same time, all of the UM or DM contacts return to their normal state and the valve control circuit is returned to its original state. The elevator then decelerates from its approach speed down to a stop due to the action of normally open valves 24b and 26b. Since the elevator has been brought to its correct approach speed before it reaches the leveling zone, it will come to rest very closely aligned with the desired floor level. In most cases, however, it will be desirable to include a leveling circuit in the elevator control system to bring the elevator car to an exact level with the selected floor and to hold it at this level as long as the elevator remains stopped. This leveling circuit can comprise a set of leveling valves coupled to conduit 92 of hydraulic control means 28 (FIG. 2), a leveling valve control circuit in electrical control means

22, and a level sensor in the elevator shaft. The level sensor can comprise any suitable prior art device, as for example the level sensor described in said U. S. Patent Number 2,913,070. The leveling valves can comprise any suitable prior art valve arrangement for adding a small amount of fluid to or bleeding a small amount of fluid from hydraulic ram 12 when hydraulic control means 28 is in its neutral position. (It will be noted, in FIG. 2, that conduit 92 is coupled directly to hydraulic ram 12 in the neutral position of valve stem 40.) The leveling valve control circuit can comprise any suitable circuit adapted to switch conduit 92 to the fluid source when the elevator car is below its desired level, as indicated by the output of the level sensor, and to switch conduit 92 to the fluid sink when the elevator car is above its desired level. The exact details of the level sensor, leveling valves, and leveling valve control circuit will not be disclosed in this document, since this invention is concerned with speed control rather than with leveling, but leveling systems of this type are well known to those skilled in the art and any suitable prior art leveling systems can be used in connection with this invention.

For a high speed run in the down direction, the above described cycle of operation is identical except for direction. Motion in the downward direction is controlled by down direction solenoids VSD, DF, DSA, DSD, DFA and DAL. Each of these down direction relays is analogous to the corresponding up direction relay described above and each connected in an identical contact circuit to duplicate the above described sequence of operation for long runs in the down direction. The relay meter circuits, of course, operate the same for either the upward or downward direction of travel.

On short runs in the up or down direction, the operation of the up and down relays is controlled by the XU, XD, and X relays shown in FIG. 4b. As mentioned earlier, a short run is initiated by momentarily closing the SP contacts and permanently closing either the UM or DM contacts depending on whether the short run is in the up or down direction. When the SP contacts are momentarily closed, solenoids XU and XD will be energized by normally closed contacts X₁, HS₁, and SP₂ as soon as the SP contacts are returned to their normal position. If the short run is to be in the up direction, solenoid XU will energize solenoids UF, USA, and UFA through normally open contacts XU₁, XU₂, and XU₃. These solenoids will in turn energize hydraulic valve 26a, 26b, and 26c, which will accelerate the elevator car upward at a fast rate of acceleration. When the speed of the elevator reaches approximately 150 feet per minute, contact FU of selector switch 74 breaks and de-energizes solenoid UFA, thereby dropping out the fast acceleration hydraulic control valve 26a. The upward acceleration then continues at a slower rate until the elevator reaches approximately 250 feet per minute, at which time contacts EU of selector switch 74 breaks and de-energizes solenoid USA, which drops out hydraulic control valve 26c and stops all acceleration in the hydraulic control means. The elevator then travels at approximately 250 feet per minute until it reaches the slow speed approach zone for the selected floor, which is indicated by the closure of a set of contacts APP which are actuated by vanes in the elevator shaft. The closure of contacts APP energizes solenoid X, which latches itself closed through normally open contacts X₂. When solenoid X is energized it breaks normally closed contacts X₁, thereby de-energizing solenoids XU and dropping out all of the hydraulic control valves in the hydraulic control means. The elevator then decelerates down towards its approach speed, and the deceleration is arrested at the approximate approach speed by the BU contacts of the selector switch means and solenoid VSU, which operates on the slow speed run just as it did on a high speed run. If the speed of the elevator is above the desired approach speed when solenoid VSU is energized, the speed will be pulsed down by solenoid TAC2,

just as it was in a high speed approach. When the elevator enters its leveling zone, which is the same on slow speeds as it is on high speeds, the VSU solenoid is de-energized by contacts LV₁, and the elevator decelerates to stop at the selected floor level. The UM contacts then drop, thus returning the valve control circuit to its original condition, and the leveling circuit takes over to level the elevator. It will be noted that deceleration relay USD is removed from the circuit by contacts XU₄ during the accelerate and constant speed portions of the short run. This is necessary to prevent USD from being energized through contacts SP₄, which are only opened momentarily in the short run. Relay USD is, however, connected back into the circuit in the deceleration portion of the run, which is initiated by de-energizing relay XU.

The above described sequence of operation is repeated for short runs in down direction by means of the X relays and the down direction relays. On high speed runs in either direction the X relays are removed from the circuit by normally closed contacts HS₁, which open at a speed of approximately 360 feet per minute in this particular embodiment. During the short run, of course, the elevator does not have time to reach 360 feet per minute and contacts HS₁ consequently remain closed for the duration of the short run.

From the above described sequence of operations it will be apparent that the valve control circuit of this invention utilizes the signals from the selector switch 74 to control the approximate speed conditions of the elevator, and that the relay meter circuits are used to make adjustments if the approximate speeds are not within predetermined limits of the actual speed of the elevator car as measured by tachometer 72. It will also be noted that smooth accelerations and decelerations are achieved in part by utilizing the natural inertia of the hydraulic valve means, which take time to move from one position to another. The rate of acceleration set by the mechanical inertia of the hydraulic valve means can be increased artificially if desired by coupling a dash pot or the like to the stem 40 of the hydraulic valve means. It will further be apparent that approximate overspeed protection is provided by the selector switch circuit per se, and that this overspeed protection is augmented by exact overspeed protection from the tachometer and relay meter circuits. Therefore, it will be clear that the automatic speed control system of this invention provides smooth acceleration and deceleration, equalization of speed under varying load conditions, and overspeed protection for hydraulic elevator systems.

Although this invention has been described and illustrated with reference to a specific embodiment thereof, it should be understood that the invention is by no means limited to specific structure disclosed herein, since many modifications can be made in that structure without departing from the basic teaching of this invention. For example, although it is preferable to integrate the approximate speed and exact speed control means, as disclosed herein, it is not necessary to do so in every embodiment of the invention. The approximate speed control means and exact speed control means can be used independently of each other if desired by making circuit alterations which will be apparent to those skilled in the art. Furthermore, it is not necessary to use the exact circuits shown herein to generate the deceleration pulses, or to use the particular brush and wiper structure shown herein as the selector switch means. A rotary selector switch can be used if desired, and the pulsating relay circuits could be replaced by continuously energized circuits without altering the basic operation of the overspeed circuit. These and many other modifications of the disclosed structure will be apparent to those skilled in the art, and this invention includes all modifications falling within the scope of the following claims.

We claim:

1. A hydraulic elevator speed control system for use

in combination with a hydraulic elevator system containing an elevator car, a hydraulic ram adapted to move said car up and down, and hydraulic valve means coupled to said hydraulic ram to control the operation thereof, said hydraulic valve means containing a movable member adapted to regulate the flow of hydraulic fluid therethrough, said speed control system comprising tachometer means coupled to said elevator to measure the speed of movement thereof, said tachometer means being adapted to produce an output signal proportional to the speed of said elevator car, threshold circuit means coupled to said tachometer means, said threshold circuit means having an "off" state and an "on" state and being adapted to switch from its "off" state to its "on" state whenever the output signal of said tachometer exceeds a predetermined value and being adapted to switch from its "on" state to its "off" state whenever the output signal of said tachometer drops below said predetermined value and valve control means coupled between said threshold circuit means and said movable member of said hydraulic valve means, said valve control means being adapted to move said movable member in response to the "on" state of said threshold circuit means in such direction as to reduce the flow of hydraulic fluid through said hydraulic valve means by a predetermined amount, thereby reducing the speed of said elevator car down to a speed corresponding to said predetermined value of said tachometer output signal.

2. A hydraulic elevator speed control as defined in claim 1 and also including selector switch means coupled to said movable member of said hydraulic valve means, said selector switch means being adapted to generate output signals in response to predetermined positions of said movable member, said selector switch means being coupled to said valve control means, and said valve control means being responsive to the output signals of said selector switch to retard movement of said movable member beyond a predetermined position thereof.

3. The combination defined in claim 2 wherein said threshold circuit comprises a relay meter and a relay multivibrator circuit coupled to said relay meter, and wherein said valve control circuit includes a pulser valve adapted to move said movable member when actuated, and wherein said output pulses from said relay multivibrator serve to actuate said pulser valve.

4. The combination defined in claim 3 wherein said selector switch means comprises an electrical switch having a fixed switch section and a movable switch section and switch contacts communicating therebetween, said movable switch section being coupled to said movable member of said hydraulic valve means, and said contacts being adapted to close and to open at predetermined positions of said movable switch section.

5. A hydraulic elevator control system for use in combination with a hydraulic elevator system containing an elevator car and a hydraulic ram adapted to move said car up and down, said elevator control system comprising a source of hydraulic fluid under pressure, a hydraulic fluid sink, a hydraulic control valve coupled between said hydraulic ram and said source of hydraulic fluid and said hydraulic fluid sink, said hydraulic control valve having a movable member therein adapted to control the flow of hydraulic fluid therethrough, said movable member being movable in an "up" direction in which said hydraulic ram is coupled to said hydraulic fluid source and a "down" direction in which said hydraulic ram is coupled to said fluid sink and having a neutral position in which fluid flow is blocked by said hydraulic control valve, the rate of fluid flow through said hydraulic control valve being proportional to the displacement of said movable member from said neutral position thereof, up valve means coupled to said movable member of said hydraulic control valve, said up valve means being operable when energized in a first mode of operation to move said movable member in the up direction thereof, and being operable when

energized in a second mode of operation to hold said movable member fixed in position, and being operable when de-energized to return said movable member to the neutral position thereof, said up valve means containing a first pulser valve adapted to move said movable member toward the neutral position thereof when energized, down valve means coupled to said movable member of said hydraulic control valve, said down valve means being operable when energized in a first mode of operation to move said movable member in the down direction thereof, and being operable when energized in a second mode of operation to hold said movable member fixed in position, and being operable when de-energized to return said movable member to the neutral position thereof, said down valve means containing a second pulser valve adapted to move said movable member toward the neutral position thereof when energized, valve control means coupled to said up valve means and said down valve means, said valve control means being adapted to energize said up valve means in its first mode of operation to move said elevator car upward and being adapted to de-energize said up valve means to terminate said upward movement of said car, said valve control means being adapted to energize said down valve means in its first mode of operation to move said elevator car downward and being adapted to de-energize said down valve means to terminate said downward movement of said car, selector switch means coupled between said movable member of said hydraulic control valve and said valve control means, said selector switch means being responsive to the position of said movable member and being operable to generate output signals at predetermined positions in the up and down direction of said movable member, said predetermined positions corresponding to approximate elevator car speeds in the up and down direction of movement thereof, said valve control means being operable to switch said up and down valve means from their first to their second mode of operation in response to said output signals from said selector switch, tachometer means coupled to said elevator car to measure the speed of movement thereof, said tachometer means being adapted to generate an output signal proportional to the speed of said elevator car, a threshold circuit coupled to said tachometer circuit, said threshold circuit having an "off" state and an "on" state and being adapted to switch from its "off" state to its "on" state when the output signal of said tachometer exceeds a predetermined level and being adapted to switch from its "on" state to its "off" state when the output signal of said tachometer drops below said predetermined level, a pulser circuit coupled to said threshold circuit, said pulser circuit being adapted to produce periodic output pulses in response to the "on" state of said threshold circuit, said pulser circuit being coupled to said valve control means, and said valve control means being adapted to energize said first and second pulser valves in response to the output pulses of said pulser circuit.

6. The combination defined in claim 5 wherein said up valve means and down valve means are adapted to be energized in a plurality of sub-modes of operation in the first mode of operation thereof, each sub-mode of operation corresponding to a different speed of movement of said movable member in the upward and downward direction thereof, and wherein said valve control means is adapted to switch said up and down valve means from one sub-mode of operation to another in response to output signals from said selector switch means.

7. The combination defined in claim 6 wherein said threshold circuit comprises a relay meter, and wherein said pulser circuit comprises a relay multivibrator circuit coupled to said relay meter.

8. The combination defined in claim 7 wherein said selector switch means comprises an electrical switch having a fixed switch section and a movable switch section and switch contacts communicating therewith, said

movable switch section being coupled to said movable member of said hydraulic valve means, and said contacts being adapted to close and to open at predetermined positions of said movable switch section.

9. The combination defined in claim 8 wherein said hydraulic control valve comprises a hollow valve casing having a movable valve stem mounted therewithin, said valve casing having a first, second, third, and fourth openings formed therein, said first opening being adapted to be coupled to said hydraulic ram, said second opening being adapted to be coupled to said hydraulic fluid source, said third opening being adapted to be coupled to said fluid sink, and said fourth opening being adapted to be coupled to said up and down valve means, a first piston member rigidly attached to said valve stem within said valve casing, said first piston member being adapted to couple said first opening to said second opening when moved in a first direction and being adapted to couple said first opening to said third opening when moved in the other direction and having a neutral position in which said first opening is disconnected from all of said other openings, the degree of coupling between said first and second and first and third openings being proportional to the displacement of said first piston member from the neutral position thereof, a second piston member rigidly attached to said valve stem within said valve casing, said second piston member having a first face which is coupled to said second opening in all positions of said valve stem and a second face which is coupled to said fourth opening in all positions of said valve stem, said first face having a smaller surface area than said second face so as to develop a net force on said second piston member when the fluid pressure at said second and fourth openings is equal, and wherein said up and down valve means is adapted to couple said fourth opening to said hydraulic fluid source to move said valve stem in one direction and to couple said fourth opening to said hydraulic fluid sink to move said valve stem in the other direction and to close said fourth opening to hold said valve stem in position.

10. The combination defined in claim 9 wherein said up and down valve means comprises a pilot valve having a second hollow valve casing and a second movable valve stem mounted therewithin, said second hollow valve casing having first, second, and third openings formed therewithin, a third piston member rigidly attached to said second valve stem, said third piston member being adapted to couple said first opening to said second opening when moved in a first direction and being adapted to couple said first opening to said third opening when moved in the other direction and having a neutral position in which said first opening is disconnected from said second and third openings, said second valve stem being coupled to said first mentioned valve stem to follow the movement thereof and being aligned with said first mentioned valve stem so as to be in its neutral position when said first mentioned valve stem is in its neutral position, said first opening of said pilot valve being coupled to said fourth opening of said hydraulic control valve, said second opening of said pilot valve being coupled to said fluid source through a first normally open valve, said third opening of said pilot valve being coupled to said fluid sink through a second normally open valve, said fourth opening of said hydraulic control valve being coupled to said fluid source via a first normally closed valve and being coupled to said fluid sink via a second normally closed valve, a first normally closed pulser valve coupled in parallel with said first normally open valve, a second normally closed pulser valve coupled in parallel with said second normally open valve.

11. The combination defined in claim 10 wherein said up valve means is energized in its first mode of operation by simultaneously energizing one of said normally open and one of said normally closed valves, and wherein said

up valve means is switched to its second mode of operation by de-energizing said one normally closed valve, and wherein said up valve means is de-energized by de-energizing said one normally closed valve and said one normally open valve, and wherein said down valve means is energized in its first mode of operation by simultaneously energizing the other of said normally open and the other of said normally closed valves, and wherein said down valve means is switched to its second mode of operation by de-energizing said other normally closed valve, and 10 wherein said down valve means is de-energized by de-

energizing said other normally open and normally closed valves.
